UNITED STATES PATENT OFFICE.

WILLIAM P. GAMBER AND WILLIAM A. PINCKNY, OF STANTON, MICHIGAN.

BUILDING-BLOCK.

No. 861,964.

Specification of Letters Patent.

Patented July 30, 1907.

Application filed January 30, 1907. Serial No. 354,953.

To all whom it may concern:

Be it known that we, WILLIAM P. GAMBER and WILLIAM A. PINCKNY, citizens of the United States, residing at Stanton, in the county of Montcalm and State of Michigan, have invented new and useful Improvements in Building-Blocks, of which the following is a specification.

The invention relates to an improvement in building blocks of the type known as hollow building blocks which are constructed to provide an intermediate air space.

The main object of the present invention is the provision of a building block comprising spaced walls which are so arranged and connected as to provide a practically uninterrupted air space between them and co-extensive with the height and length of the walls.

The invention will be described in the following specification, reference being had particularly to the accompanying drawing, in which:

20 Figure 1 is a perspective view of a building block constructed in accordance with our invention, Fig. 2 is a horizontal transverse section of the same, Fig. 3 is a vertical transverse section of the same, Fig. 4 is a top plan of the same, Fig. 5 is a transverse section of the block shown in Fig. 1, illustrating particularly the means for maintaining the walls in position after molding and during final setting, Fig. 6 is a section on line 8—8 of Fig. 7, Fig. 7 is a plan view of the block with the wall holding means in applied position.

30 Referring particularly to the drawing, our improved building block comprises walls 1 and 2, preferably molded of any desired plastic material, and constructed of any dimensions to provide a block of the desired size. The walls 1 and 2 are, in the completed article, 35 maintained in spaced parallel relation, and the present invention is directed to the provision of means for securing the walls in such position under all uses to which the block may be put, while at the same time avoiding any material obstruction in the space between 40 the walls.

In Figs. 1 to 4 inclusive is illustrated the preferred form of connection between the walls 1 and 2, which in this instance comprises duplicate sections of wire, or similar material, as 3, which is bent longitudinally 45 into sinuous form to provide cross bars 4. The wire sections 3 are embedded in the walls 1 and 2, being arranged respectively adjacent the upper and lower edges of the walls, with the cross strips 4 bridging the space between the walls. The rounded portions 5 of 50 the wire strips connecting the cross bars in the formation of said strips are thus embedded in the material of the walls, thereby effectively securing the walls in spaced parallel relation with the opening between them, which is co-extensive with the length and 55 height of the wall, interrupted only by the cross bars 4 of the strips.

By preference the respective strips 3 are arranged in relatively inclined positions transverse the block, the embedded portions of the strips in one wall being disposed nearer the respective upper and lower edges of 60 that wall than the similarly embedded portion in the opposing wall, as clearly shown in Fig. 3. The cross bars 4 of each section are also inclined relative to each other, as shown in Fig. 4, which in addition to the relative inclinations of the respective strips tends to more 65 effectively prevent independent movement of either wall under lateral strain.

In Figs. 5 to 7 inclusive is shown a simple means for properly supporting the walls after molding and during final setting. In carrying out this feature of the 70 invention, we provide mold plates 8 and 9 designed to be arranged against the inner surfaces of the respective walls between the wire sections connecting said wall. Additional mold plates 10 and 11 are arranged to bear against the respective inner surfaces of the wall 75 above and below the wire connectors, said plates 10 and 11 being preferably notched on their lower edges to engage the cross bars of said wire connectors. Wedge keys 12, in any suitable or desired number are to be driven between the plates 10 and 11 from above and 80 below the blocks, said keys also engaging and spreading the plates 8 and 9. The plates 8 and 9 are preferably inclined on their respective upper and lower edges from the inner surfaces of said plates downwardly toward their outer or wall engaging surfaces, so that upon 85 withdrawal of the wedges 12 said plates 8 and 9 will fall toward each other to facilitate their removal.

The building blocks constructed as described will, therefore, include side walls which are maintained in spaced parallel relation, with the connecting medium 90 of sufficient strength to maintain them in such relation and yet of such size as to afford the minimum obstruction to the air space between the walls.

In using the blocks from the wall of a building structure, it will be obvious that said wall will be formed 95 with an intermediate air space which is practically co-extensive in width and height with the wall, thereby affording the maximum resistance to the passage of atmospheric influences.

In addition to the advantage of the maximum air 100 space, the building block of this invention is of extreme simplicity in manufacture, requiring no special tools or special form of mold for its production, thereby enabling the blocks to be manufactured at a low cost and readily adapting them for use in all classes of building 105 structures.

Having thus described the invention what is claimed as new, is:

1. A building block comprising spaced walls and a plurality of connectors embedded in said walls during molding, each of said connectors having a series of integral sections disposed at an angle to each other and arranged 110

to bridge the space between the walls, said sections being arranged in the same plane longitudinally of the block and in respectively spaced relations, said connectors being relatively inclined to each other and to the block.

2. A building block comprising spaced walls and a plurality of connectors embedded in said walls during molding, each of said connectors having a series of integral sections arranged to bridge the space between the walls throughout the length of the latter, being arranged in the same plane longitudinally of the block and respectively

inclined with relation to each other, the respective connectors being inclined relative to the upper and lower edges of the walls and to each other.

In testimony whereof, we affix our signatures in presence of two witnesses.

WILLIAM P. GAMBER.

WILLIAM A. PINCKNY.
